UNITED STATES PATENT OFFICE

TOTILA MADLUNG, OF DESSAU IN ANHALT, GERMANY, ASSIGNOR TO I. G. FARBEN-INDUSTRIE AKTIENGESELLSCHAFT, OF FRANKFORT-ON-THE-MAIN, GERMANY, A CORPORATION OF GERMANY

REELING OF ARTIFICIAL THREADS

Application filed August 31, 1928, Serial No. 303,295, and in Germany September 15, 1927.

The present invention relates to improvements in the reeling of artificial threads from a centrifugal cake and to devices suitable thereto.

- 5 In spinning artificial fibers in a centrifuge box, the thread collects on the inner surface of the box and forms the so-called centrifugal cake. This cake is reeled off to produce the hanks of thread. During the reeling operation the thread remains remarkably sensitive so that the quality of the product depends very much on the smooth and uninterrupted running of the reeling operation. On this account various devices have been 15 constructed with a view to facilitating and improving the reeling operation. All such devices are for the purpose of ensuring an uninterrupted flow of the thread from the beginning to the end of the centrifugal cake. 20 For example, the cake has been mounted on a wooden or metal cone, or there have been inserted in the cake circular springs to act as a brake.

According to the present invention the 25 reeling of the thread is conducted easily and smoothly by mounting the centrifugal cake on a body of rubber or other elastic material, which is then inflated. The inflated body bears against the inner surface of the cake 30 and acts very advantageously as the support which the cake needs in order that the thread may be reeled smoothly.

By using a device of this kind, the cake can be reeled off from beginning to end quite 35 uniformly and the waste in the process is reduced to a minimum. In particular, the device has the advantage that any friction or damage to the cake at starting is avoided. Moreover, the rubber body being inflated the 40 pressure on the cake in every direction is uniform and gentle and prevents collapse of the cake without pushing any part of the latter against its support. The cake can be carried free by the body, that is to say its 45 lower edge need not come in contact with any surface, although it can be allowed to rest on a base plate, if desired, with which the body may be provided.

In the attached drawing I have illustrated 50 several preferred forms of the invention; it

being understood that no limitations to the precise structural details disclosed are necessary, but changes, alterations, and modifications within the scope of the claims may be resorted to.

Figures 1 to 4 show cross sections of my new supports bearing a fiber cake.

In the several figures the same reference characters are used throughout to designate equivalent parts. A represents an elastic bag. B is the centrifugal cake mounted on the bag. C is a connecting tube for the inflating pump, said tube is attached to the base plate E. It may be provided with a valve D. The form of the bag can be varied within wide limits and the base plate E may be of various form. The air-tight joint between the base plate may be made in any suitable manner. In Figure 1 the bag A covers completely the outside of the base plate E. In Figure 2 a ring F is arranged upon the base plate E and the bag A is air-tight attached to the base plate E by placing its lower ends A' continuously between the base plate E and ring F and pressing the same against the base plate with screws G. In Figure 3 grooves E' are arranged in the lateral surface of the plate E, the bag A is placed over said lateral surface and air-tight attached to this surface by pressing it into the grooves E' by means of a wire H or the like. In Figure 4 the elastic bag A is placed over the lateral surface of the base plate and pressed thereupon by means of a ring I.

What I claim is:

1. As a support for a centrifugal cake of artificial threads in the reeling process, a base plate and an elastic bag which is air tight attached to said base plate, said base plate being provided with a tube which connects the outside with the interior of said bag.
2. As a support for a centrifugal cake of artificial threads in the reeling process, a base plate and an elastic rubber bag which is air tight attached to said base plate, said base plate being provided with a tube which connects the outside with the interior of said bag.
3. As a support for a centrifugal cake of

artificial threads in the reeling process, a base plate which is provided with grooves in its lateral surface, an elastic bag which is placed over said lateral surface and air-tight
5 attached thereto by pressing the bag into the grooves by means of wire, said base plate being provided with a tube which connects the outside with the interior of the bag.

4. As a support for a centrifugal cake of
10 artificial threads in the reeling process, a base plate which is provided with grooves in its lateral surface, an elastic rubber bag which is placed over said lateral surface and air-tight attached thereto by pressing the
15 bag into the grooves by means of wire, said base plate being provided with a tube which connects the outside with the interior of the bag.

In testimony whereof, I affix my signature.
